US0D1103814S

(12) **United States Design Patent** (10) **Patent No.:** **US D1,103,814 S**
(45) **Date of Patent:** **** Dec. 2, 2025**

(54) **RFID TAG**

(71) Applicant: **NSK Ltd.**, Tokyo (JP)

(72) Inventors: **Shigeru Endou**, Kanagawa (JP);
Masateru Kondou, Kanagawa (JP);
Daisuke Abe, Kanagawa (JP); **Masaki Kuwahara**, Kanagawa (JP)

(73) Assignee: **NSK LTD.**, Tokyo (JP)

(**) Term: **15 Years**

(21) Appl. No.: **29/967,602**

(22) Filed: **Oct. 11, 2024**

(30) **Foreign Application Priority Data**

Apr. 17, 2024 (JP) ..... 2024-007941 D

(57) **CLAIM**

The ornamental design for a RFID tag as shown and described.

DESCRIPTION

FIG. 1 is a front perspective view of an RFID tag showing our new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged cross-sectional view taken along line 9-9 in FIG. 3; and,

FIG. 10 is a cross-sectional view taken along line 10-10 in FIG. 3.

The broken lines depict portions of the RFID tag that form no part of the claimed design.

1 Claim, 5 Drawing Sheets
